UNITED STATES PATENT OFFICE.

WALTER KENNEDY, OF ALLEGHENY, PENNSYLVANIA.

PLANT FOR COKE-MAKING.

SPECIFICATION forming part of Letters Patent No. 691,148, dated January 14, 1902.

Application filed May 24, 1901. Serial No. 61,741. (No model.)

To all whom it may concern:

Be it known that I, WALTER KENNEDY, a citizen of the United States, residing at Allegheny, in the county of Allegheny and State 5 of Pennsylvania, have invented or discovered certain new and useful Improvements in Plants for the Manufacture of Coke, of which improvements the following is a specification.

The invention described herein relates to 10 certain improvements in plants for the manufacture of coke, and has for its object a construction and combination of elements whereby the coke can be easily removed from the coking-hearth and charged into a car, in 15 which it can be quenched or transferred to a quenching or storage bin.

It is a further object of the invention to provide for the utilization of the products generated during the burning of the coal.

20 The invention is hereinafter more fully described and claimed.

In the accompanying drawings, forming a part of this specification, Figure 1 is a view, partly in end elevation and partly in section, 25 of my improved plant. Fig. 2 is a top plan view of the plant. Fig. 3 is a side elevation of the same. Fig. 4 is a plan view of a portion of the plant, showing a modification of the utilization of the gaseous products. Figs. 30 5 and 6 are sectional elevations on planes indicated by the lines V V and VI VI, Fig. 4. Figs. 7 and 8 are detail views showing the detachable connection between the oven and gas-main. Fig. 9 is a sectional detail view on 35 a plane indicated by the line VIII VIII, Fig. 4; and Fig. 10 is a top plan view of the buggies or trolleys employed for hoisting and shifting the ovens, &c.

In the practice of my invention two lines 40 of hearths 1 and 1^a are formed on opposite sides of a line of rails 2 and in such relation thereto as to permit the passage of a car A between the hearths and with the bottom of the car on a level with the upper surface of 45 the hearths. Under each of the hearths are formed a series of flues 3, which connect at their outer ends to combustion-chambers 4 4^a, into which gas may be introduced, as herein-after described. At their inner ends these 50 flues connect with sewers or flues 5 and 5^a, which in turn connect with a suitable stack. (Not shown.) The car or cars are

provided on their sides with hinged plates 6, which when turned up will form retaining sides for the car, but when turned down form 55 continuations or prolongations of the car-bottom and extend to the edges of the hearths, so that the floors of the cars and the upper surfaces of the hearths, which are on a common level, or approximately so, are connected 60 by bridges formed by the plates 6. On these hearths are arranged a series of two or more ovens 7 7^a, consisting of an arch framework formed within metal shells 8, so as to permit of the handling of these ovens, as will be hereinafter described. The tops of the ovens are provided with openings 9, through which fresh fuel may be charged thereto; but these openings are normally closed by stoppers 10 while coking is being effected. Flues 11, 70 formed in the walls of the oven, are connected at their inner ends with the oven, while their outer ends are adapted to be connected to gas-mains 12 12^a. The connections between the gas-mains and the flues 11 are formed by 75 pipes 13 13^a, having their outer ends connected to sliding plates 14 14^a, which are held in contact with plates 15 15^a, formed on the outer ends of nozzles 16 16^a, projecting from the conduits or pipes 12 12^a, by means of 80 weighted levers 17 17^a, pivoted to the pipes 12 12^a and having rollers 18 so mounted thereon as to bear upon the upper surfaces of the plates 15 15^a. The outer ends of these levers are weighted, so that with the rollers 85 18 forming the fulcrum they will hold the plates 14 closely in contact with the plates 15. The plates 14 and pipes 13 are shifted along the plates 15 by means of pinions on 90 the shafts of hand-wheels 19 engaging racks 95 formed on the plates 14, the shafts of said hand-wheels being mounted in bearings secured to the plate 15. By this construction the pipes 13 13^a can be moved toward and from the flues 11 11^a as required. Openings 100 are formed through the plates 14, which will register with the nozzles 16 when the inner ends of the pipes 13 (said ends having supports 13^b) have been adjusted or shifted into the ends of the flues. When the pipes are shifted away from the flues, blank portions of the plate 14 will cover the nozzles 16 and prevent any escape of gas from the conduit. The gases generated within the ovens may be

conducted by the conduits 12 12^a to any suitable point, where they may be washed or otherwise treated to save the by-products, or the gas may be utilized for heating purposes. 5 When the gas is used for heating the hearths, the conduits 12 are provided with a series of branches 20 20^a, which extend down to boxes 21 21^a. These boxes are adapted to be connected to the combustion-chambers 4 4^a by 10 means of a valve mechanism and pipe 22, similar to that described above for connecting the conduits 12 to the flues 11. In lieu of burning the gases as they come from the coke-ovens they may be conducted to a point 15 where the by-products can be eliminated and then returned through conduits 23, which are provided with a series of branches 24, having their lower ends connected to the boxes 21. Where both conduits 12 and 23 are connected 20 to the boxes 21, a valve 25 is employed for the purpose of connecting the one or the other of the branches 20 and 24 with the boxes. This construction permits of the use of the gas either before or after the elimination of the 25 by-products.

After the charge of coal has been coked in an oven the latter is slid along the hearth and across the bridge 6 and onto the car, carrying with it the charge of coke, which is still 30 in a highly-heated condition. The oven is then raised, leaving the charge on the car, and returned to the hearth. A desirable mechanism for this purpose consists of an overhead crane. This crane consists of a bridge 35 25, provided with rollers at its ends adapted to move along rails 26, which are supported by a suitable framework extending along the entire line of ovens. On the bridge is mounted a buggy 27, having wheels 28, adapted to move 40 along rails on the bridge. This buggy is adapted to be shifted by any suitable form of motor known in the art—as, for example, by an electric motor 51, having its arms or shaft connected by suitable gearing to one or both 45 of the axles of the wheels 28 of the buggy. Four rods 29 extend down from the buggy on each side of the bridge and have their lower ends connected to cross-bars 30, provided with hooks 31, adapted to engage pins 32, secured 50 to the sides of the ovens. These rods 29 are preferably braced by rods 33 and are held in position laterally by means of friction-rollers 34, carried by the rods and bearing against guide-frames 35, depending from the buggy. 55 Any suitable means may be employed for raising and lowering the rods and with them the ovens—such, for example, as nuts 36, fitting over the threaded upper ends of the rods. The peripheries of these nuts, which rest upon 60 suitable abutments 37 on the buggy, are provided with teeth suitably constructed to engage worms on the outer ends of shafts 38, having pinions 39 keyed to the inner ends. These pinions intermesh with pinions 52 on 65 shafts driven by any suitable motor 53, so as to raise or lower the rods and the ovens hung thereon. When it is desired to shift an oven

from the hearth onto the car, the buggy is moved along to a suitable position over the oven and the rods lowered, so that the hooks 70 31 may engage the pins 32 by a lateral movement. Then the rods are raised sufficiently to shift the oven out of contact with the hearth. The buggy is then shifted along the bridge by its motor, thereby carrying with it 75 the oven and sliding the charge contained therein over the hearth onto the car. The oven is next raised and moved back again to position onto the hearth, where a new charge of coal is placed therein, and its flue 11 connected to the gas-conduit 12. The coke may be quenched as soon as the oven is removed or may be carried along in the car to a suitable point, where it may be dumped into a tank containing water and thence removed 80 by any suitable means to cars or a point of storage. It is preferable, however, to effect the quenching of the coke while in the car by means of steam, and to this end a cover 40 is provided for the car. As soon as the coke is 85 placed in the car the side or sides 6 thereof are turned up, the oven removed, and the cover 40 placed over the car. Steam is next forced into the car through the nozzles projecting from the pipes 41 through the sides of 90 the car. This pipe is connected to a feed-pipe 42, secured to the car and adapted to be connected by a coupling to a suitable steam-supply, as the boiler of a locomotive. An auxiliary trolley 43 is mounted upon rails secured to the bridge 25 for the purpose of handling the cover of the car. This buggy or trolley is provided with a suitable shifting-motor 54 and lifting-motor 55. The bottom of the car is preferably formed of pivoted sections to permit of the ready removal of the coke therefrom.

At one end of the line of ovens an elevated track 44 may be arranged for coal-cars, so that the coal may be discharged down a suitable chute into a bucket 45, suspended from a buggy 46, mounted on an auxiliary bridge 47 on the rails 26. The bucket 45 is formed with a discharge-opening in its bottom, so that the coal may be discharged easily into 115 the ovens.

For the purpose of storing the coke and charging into cars elevated bins 48 are arranged at one end of the line of ovens. The coke is discharged from the car A into the 120 hoist-chute 49, from which it passes into the hoisting-cars 50, arranged on rails passing up over the bins 48. The cars 50 and rails are constructed to effect an automatic dumping of the charge into the bins.

I claim herein as my invention—

1. In an apparatus for manufacture of coke the combination of a hearth, one or more ovens movably arranged on the hearth, a car having a movable side arranged in such relation to the hearth that the movable side will form a bridge from the car-bottom to the hearth and means for shifting the oven and its charge from the hearth over the bridge onto the car 130

and for lifting and returning the oven to the hearth, substantially as set forth.

2. In an apparatus for manufacture of coke, the combination of two lines of hearths, two series of two or more ovens movably arranged on the hearths, a car movable between the lines of hearths, a bridge movably mounted on rails parallel with the hearths, a buggy movably mounted on the bridge and hoisting mechanism arranged on the buggy and adapted to be connected to the ovens in turn, substantially as set forth.

3. In an apparatus for manufacture of coke, the combination of a hearth, a series of two or more ovens movably arranged on the hearth, a gas-conduit extending along the line of ovens, movable connections between the ovens and conduit and valves controlling such connections, substantially as set forth.

4. In an apparatus for manufacture of coke, the combination of a hearth provided with heating-flues, a series of two or more ovens movably arranged on said hearth, a gas-conduit extending along the line of ovens, movable connections between the ovens and conduit, valves controlling such connections, branches extending from the conduit to the hearth, heating-flues and valves controlling such branch connections, substantially as set forth.

5. In an apparatus for manufacture of coke,

the combination of two lines of hearths, two series of two or more ovens movably arranged on the hearths, a car movable between the lines of hearths, a bridge movably mounted on rails parallel with the hearths, a buggy movably mounted on the bridge, rods extending down from the buggy and provided with means for engaging the ovens, means for raising and lowering the rods, and guides for holding the rods as against lateral movement, substantially as set forth.

6. In an apparatus for the manufacture of coke, the combination of a line of two or more hearths, one or more movable ovens having open bottoms adapted to be supported by said hearths, an oven-hoisting mechanism movable along the line of hearths and means for detachably connecting the hoisting mechanism to the oven or ovens, substantially as set forth.

7. In an apparatus for the manufacture of coke, the combination of a line of two or more hearths, one or more movable ovens having open bottoms and mechanism for hoisting and shifting the ovens, substantially as set forth.

In testimony whereof I have hereunto set my hand.

WALTER KENNEDY.
